UNITED STATES PATENT OFFICE.

JOHN JAMES ARMSTRONG, OF LOS ANGELES, CALIFORNIA.

CALANDRIA.

Application filed September 9, 1920. Serial No. 409,064.

To all whom it may concern:

Be it known that I, JOHN J. ARMSTRONG, a citizen of the United States, residing at Los Angeles, county of Los Angeles, State 5 of California (whose post-office address is Higgins Building, Los Angeles, California), have invented certain new and useful Improvements in Calandrias; and I do hereby declare the following to be a full, clear, and

10 exact description of the invention, such as will enable others skilled in the art to which it appertains to make and use the same.

This invention relates to an improved 15 form of calandria for use in connection with either multiple effect evaporators or vacuum pans and has particular reference to the type generally known as the tube-sheet type.

In calandrias of this type heretofore used, the tubes were set either vertically, regard- 20 less of the angle at which the tube-sheets were placed or were disposed at right angles to the tube-sheets, but in both instances the top and bottom tube-sheets were arranged parallel to each other, irrespective of the 25 angle from the horizontal at which said tube-sheets were positioned.

The principal and distinguishing feature 30 of this invention resides in the position of the top tube-sheet with respect to that of the lower tube-sheet, the top tube-sheet being placed horizontally or approximately so, and the lower tube-sheet placed on an angle from the horizontal, the tubes being vertically disposed in relation to the calandria 35 as a whole. By this arrangement a better distribution of heat is assured and a greater heating surface obtained, as compared to calandrias of a corresponding height, the height referred to being that of the calan- 40 dria where it is supported in the walls of the vacuum pan or evaporator.

Briefly stated, the invention comprises a calandria having an upper or top tube-sheet, horizontally arranged, provided with the 45 customary large central opening and a series of smaller openings, which latter openings are to accommodate the upper ends of the vertically arranged heating tubes. The bottom or lower tube-sheet is arranged at an 50 angle to the horizontal, being also provided with a large central opening and a series of vertically disposed smaller openings to accommodate the lower ends of the heating tubes in position between the upper and lower tube-sheets, the two large central open- 55 ings of said upper and lower tube-sheets

being connected by a corresponding large cylinder or tube forming the central opening of the calandria, the calandria when assembled being positioned and supported in 60 the walls of the vacuum pan in the customary manner, means also being provided for the entrance of the necessary steam for furnishing the desired heat during the operation of the apparatus.

Referring particularly to the accompanying drawing illustrating the preferred embodiment of the present invention, the calandria designated generally as A is supported in the walls of the vacuum pan or evaporator B. The calandria A comprises an upper tube-sheet 1 arranged in substantially horizontal position and a lower tube-sheet 2 disposed at an angle to the horizontal, resulting in a gradual increase in depth of the 75 calandria from the outer periphery toward the center thereof. The top tube-sheet 1 is provided with a series of uniformly arranged openings 3, which are adapted to receive and have secured therein vertically disposed heating tubes 4.

The lower tube-sheet 2 is likewise provided with a series of uniformly arranged and vertically disposed openings 5, said openings being positioned directly beneath 85 and concentric with corresponding openings 3 of the tube-sheet 1, in order to receive the lower ends of the heating tubes 4, positioned between and extending from the horizontally arranged tube-sheet 1 and the angularly disposed tube-sheet 2.

Tube-sheets 1 and 2 are also provided with large central openings 6 and 7, respectively, which openings are connected by a correspondingly large cylinder or tube 8, providing the customary large central opening usually employed in calandrias of this type.

Extending around the outside of the calandria A is an enclosing rim or the like 9, provided with steam inlets 10, the calandria when assembled being positioned in and supported by the walls of the evaporator or vacuum pan B in the customary manner. The central tube 8 at its lower end is constructed with an outlet opening 11 connected to a pipe 12, furnishing the necessary means of draining the calandria of the condensate through the lower portion of the vacuum pan B.

This improved arrangement allows for a 110 gradual increase in the length of the heating tubes from the outer periphery of the

calandria toward the center thereof, resulting, as hereinbefore stated, in a better distribution of heating surface. It will be apparent that, as the heating steam travels 5 from the inlet toward the center of the calandria, the pressure, and therefore the temperature, gradually falls. This is true in all calandrias of this type, and where the heating tubes are all of the same length a greater 10 amount of heat will be present around the outer portion of the calandria than at the inner portion thereof, the tubes of equal length all presenting the same heating surface, and consequently the tubes nearest the steam 15 entrance will become much hotter than those tubes farthest removed from said steam entrance.

In applicant's construction the heating steam as it enters the calandria is constantly 20 coming in contact with tubes that are successively increasing in length and in heating surface from the outer to the inner rows and, therefore, the total heat transference of each tube is substantially equal, owing to the 25 fact that the liquor under treatment, upon passing through the longer tubes, will be heated a correspondingly increased length of times, thus furnishing a uniform degree of heat throughout the entire calandria. 30 At the same time the lower tube-sheet which remains at an angle to the horizontal, will still retain the advantages and excellent features common to all inclined calandrias, in that the effect of quick and efficient condensate drainage is obtained. 35

In calculating the lengths of the tubes in the several annular rows, it is necessary only to determine the lengths of the tubes in the outer and inner rows, as the lengths of the tubes in the intermediate rows will be a 40 mere matter of mathematical calculation. The dimensions of the tubes in the outer row being fixed and the temperature of the entering steam and the temperature of 45 vaporization of the juices in the calandria being observed, the evaporation in pounds of water per square foot of heating surface of these tubes is readily determined, which may be reduced to pounds of water per hour 50 per degree of difference between the temperature of the steam and the temperature of the medium being evaporated. Then determining the difference between the temperature of the steam surrounding the inner tubes and that of the evaporating medium, it is a mere matter of calculation or proportion to determine the relative lengths of 55 the outer and inner tubes to effect the same rate of evaporation by all of the tubes.

60 As a practical example, assume the outer tubes of a standard calandria to be 2 ft. in length, the temperature of the entering steam at 230 degrees (about 6 pounds gauge pressure) the medium being evaporated at 65 100 degrees F. (corresponding to 28 inches

of vacuum in the pan), there exists a maximum difference of temperature between the heating steam and the medium being evaporated of 230 degrees minus 100 degrees, or 130 degrees. Under these conditions, the 70 outer tubes would evaporate a maximum of 80 lbs. of water per square foot of heating surface per hour with a maximum difference of temperature of 130 degrees F., which is equivalent to .6 lb. of water per degree 75 difference, per square foot of heating surface, per hour. It has been found in practice that the difference in the temperature of the steam entering the calandria and surrounding the outer tubes and that of the steam surrounding the inner tubes is frequently as much as 40 degrees in the early stages of the boiling operation and assuming this decrease in temperature of the steam as a basis of calculation, it follows that the 80 the difference between the temperature of the steam about the inner tubes and the temperature of the medium being evaporated is about 90 degrees F., or 230 degrees—40 degrees—100 degrees. Assuming the same rate of evaporation per degree in temperature, per square foot of heating surface, per hour as above, it would obviously require a greater heating surface in the inner tubes to effect evaporation at this 85 rate, than the heating surface of the outer tubes, in the proportion of 90 degrees to 130 degrees, or about 1 to 1.44. It follows, therefore, that in a calandria having outer tubes 2 ft. long, the inner tubes must be 2 $\times$ 90 1.44 or 2.88 ft. long to produce theoretically equal and uniform evaporation by both the outer and inner tubes, the intermediate tubes taking a proportional length between these extremes. In actual practice, in a 105 calandria of the type shown in the drawing in which the outer tubes are two ft. in length and 4 inches outside diameter, the inner tubes would be approximately 3 ft. in length and the length of the intermediate tube being graduated correspondingly. 110

From the foregoing description it will be apparent that applicant has produced a calandria obviating the principal disadvantages heretofore present in calandrias of the tube-sheet type, without sacrificing the particular and important advantages of this type of calandria. Moreover, from a constructional advantage and the question of production, applicant's calandria is much 115 cheaper and far more convenient to manufacture than a calandria with both of the tube-sheets placed on an angle and parallel to each other.

What I claim is:

125 In a vacuum pan, a calandria comprising an upper horizontal tube sheet, a lower downwardly and inwardly inclined tube sheet, an inclosing rim provided with oppositely disposed steam inlets therein, a cen- 130

tral conduit connecting the sheets, and circulation tubes extending between and through said sheets, said tubes increasing in length successively from the periphery 5 towards the center of the calandria by an amount substantially commensurate with the decrease in the temperature of the steam

supplied to the calandria through the steam inlets; whereby the heating effects of all of said tubes will be substantially equal. 10

In testimony whereof I affix my signature.

JOHN JAMES ARMSTRONG.
